ORE CONCENTRATING TABLE

Erwin R. McPheters, Boise, Idaho

Application February 1, 1944, Serial No. 520,669

4 Claims. (Cl. 209—458)

1

This invention relates to ore concentrators, ore-pulp specific concentrators and separators, sluice troughs and the like, the preferred embodiment thereof being ideal for recovery and separation of raw minerals, this because it is possessed of details and an arrangement thereof which will properly and systematically classify the ores into groups according to specific gravity, whereby to provide an extra fine concentrate with three or more lower classes of concentrates as is highly desirable, for best marketing values.

Considerable difficulties and perplexing situations attend the handling and usage of present-day varied types of concentrating units in recovering the minerals in scientific and best value groups for marketing, the handlers of such units getting either one good concentrate with extra low production and too much value lost in waste, or a low grade concentrate characterized by an over-abundance of insolubles and waste.

Due to years of trained experience and research, scientifically and otherwise, conducting mine operations I am familiar with various types of ball mills, pulp conditioning, sizing and desliming machines, concentrator-type separators, sluice boxes and the like. That is to say, and in particular reference to the subject matter with which we are here concerned, I am full well aware that many and varied are the types of tables and troughs employing zig-zag sluice-ways. I can, therefore, point out with particularity that, bearing in mind the already existing devices and developments in the prior arts, I have evolved and produced a concentrator and separator construction in which an arrangement of button-like individually and selectively adjustable regulating deflectors, in alternating sequence at adjoining ends of the successive sluice-ways for grading and classifying ore pulp in its downward passage over the plate, constitutes an outstanding development and improvement with which we are here particularly concerned.

In addition to these adjustable ore pulp deflecting regulators coacting with the discharge ends of the grading channels or sluice-ways, novelty is also predicated upon the adoption and use of special type partitioning dividers, each divider having a plate on one side disposed at an angle to the main horizontal base plate, and the opposite faces or sides of said partitions being beveled to enhance settling of the graded or grouped concentrates.

Other features and advantages of the invention will become more readily apparent from the

2

following description and the accompanying illustrative drawings.

In the drawings, wherein like numerals are employed to designate like parts throughout the same—

Figure 1 is a top plan view of the ore-pulp receiving, concentrating, separating and classifying unit or table constructed in accordance with the principles of the instant invention.

10 Figure 2 is a side elevation of the complete apparatus or machine showing not only the adjustable table but the retrieving bins for the classified minerals.

Figure 3 is an end view of the structure seen in Figure 2 observing it in the direction from left to right.

Figure 4 is an exaggerated fragmentary detail view on the plane of the line 4—4 of Figure 1 looking in the direction of the arrows.

20 Figure 5 is a transverse vertical section on the plane of the line 5—5 of Figure 4.

Figure 6 is an exaggerated detail sectional and elevational view taken on the plane of the general line 6—6 of Figure 7.

25 Figure 7 is a fragmentary top plan view of the intake end of the table showing a diagonal separator or partitioning unit in which a ribbed or corrugated plate is employed to obtain a desired riffle action on the ore pulp mass.

30 The overall or complete structural arrangement may be divided, broadly into two parts; namely, A and B. The sub-structure A comprises a framework including uprights 9 with enclosing walls 10 of appropriate material and dimensions, these defining an enclosure 35 which is divided, through the medium of transverse and longitudinal divider walls 11 and 12 into classified mineral depositories or bins. As seen by dotted line picturization in Figure 1, the complete structure is divided into eight distinguishable bins.

40 The table-type separator and concentrator unit B has a slight gravity incline, the discharge end being hinged as at 13 to the corresponding end of the sub-structure A. At the opposite end of the table or trough-walls 14 are provided with suitable brackets 15 engaged by the adjustable end of raising and lowering feed screws 16 in fixed brackets 17 on the adjacent posts 9. The

45 inlet or feed means for the ore-pulp is at the left hand end of the structure, this being a channel of trough-like form 18 from the de-slusher and ball-mill or similar crusher structure. The discharge channel is at the opposite 50 end and denoted by the numeral 19. As pre-

viously indicated, the bottom of the box or table, denoted at 20, is preferably in the form of a polished steel or equivalent metal plate. This is provided at longitudinally spaced alternate points with discharge openings or holes 21 in alignment with the underlying bins. Certain of these holes are provided with short tubes or pipes 22 having hooks 23 to accommodate detachable gravity test buckets 24 made for sizing and keeping a close test on each separation step. Similar discharge pipes 25 with lateral shunting nozzles 26 serve to deliver the remaining gravity separated minerals into their depositories or bins.

The plate is provided with a plurality of staggered properly angled and arranged dividers or partition elements 27 of duplicate constructions, these dividing the plate transversely into progressively arranged sluice-ways 28. It will be noticed that the partitions 27 are so arranged as to terminate adjacent the discharge holes 21. Thus, the ore-pulp is concentrated as it leaves each sluice-way and is acted upon before it enters the next sluice-way, this through the medium of the double pointed deflector-type regulators 29. These grading regulators are in number according to the number of discharge holes or openings 21. In fact, each hole has a pulp grading regulator cooperable therewith and this is of crescent-shaped configuration and eccentrically pivoted as at 30 with one point overlying and partly valving the hole. The opposite end is provided with an arcuate slot 31 coacting with a bolt 32 and thumb nut 33 which permits proper angling and setting of said regulator 29.

In order to bring out a function in the system of operation to be later described, it is desirable to distinguish the regulators 29 successively by the numerals 1 to 8, inclusive. Reference for this is had to Figure 1 of the drawings. It is to be pointed out too, at this point, that the pitch of the table unit A is generally very slight but it is nevertheless variable to regulate it to determine for best recovery operations.

Extra water supply and delivery pipes 34 on opposite sides of the table-troughs are provided and these are, in turn, provided with jets 35 and 36 leading into the respective sluice-ways 28 to liquify the mass and to facilitate spreading the water over the plate and to thus avoid congestion and to make for faster and accurate separation.

This concentrator is designed not only to separate the metals from the waste, but to separate the heavier more precious metals from metals of different character and weight, by gravity. Metals of different gravity may be separated further after the first concentration by putting it over a second plate and watching the gravity closely.

Separators 1, 2, and 3 to be set for a specific gravity of six (6), which will recover the following minerals: gold, bismuth gold, tellurium, calaverite, nagyagite, hessite, petzite, sylvanite, silver (native), argentite, cerargyrite, stephanite, platinum, sperrylite, iridium, osmium, palladium, copper (native), cuprite, lead (galena) cerrusite, anglesite, pyromorphite, crocoite, massicot, scheelite, ferberite, hubnerite, wolframite, uranium, vanadilite, tin, cassiterite, quicksilver, cinnabar, bismuth, bismuthinite, niccolite, smaltite, and cobaltite.

Separators 4, 5 and 6 to be set at a specific gravity of four (4), which will recover the following minerals: ruby, silver, calcocite, tetrahedrite, chalcopyrite, melaconite, bornite, brochantite, 75

smithsonite, zincite, antimony, jamesonite, magnetite, red hematite, chromite, pyrolusite, molybdenite, titanium, descloizite, foleyrite, blueite, linnaeite, and cadmium.

5 Separators 7 and 8 to be set at a specific gravity of three (3) which will recover the following minerals: malachite, azurite, calamine, spalerite, limonite, siderite, manganese oxide (wad) psilomelane, rhodocrosite, volborthite, whartonite, and any of the other minerals that may be altered or oxidized, having a gravity over waste lime or quartz (2.6). By accurate setting 1, 2 and 3 will produce different grade products if desired.

10 Gravity is very accurate and efficient providing care is taken to overcome existing conditions, the main items in operating this concentrator to full efficiency is to have plenty of water flow and to crush fine to separate different metals (mechanically mixed). Chemically mixed metals will fall between the two metals on the plate.

15 The outstanding phases and features of the invention, structurally speaking, are the new and novel partitions defining and dividing the trough-like table into the zig-zag concentration areas or sluice-ways, the discharge openings at the connecting ends of the progressive sluice-ways and the valving type deflectors and regulator members 29, preferably of crescent-shaped configuration.

20 30 As brought out in Figures 4 and 5, each divider is substantially V-shaped in cross-sectional form and provides a slanting or beveled face 27a on one side. On the opposite side I provide a metal strip or plate 27b. This construction and arrangement is susceptible of accomplishing the desired fast and accurate settling of the mineral laden pulp.

25 35 Reference being had at this stage to Figure 4, I desire to call attention to the fact that the plate 27b is preferably adjustably mounted on the body 27a. This is accomplished by vertical slots 37 and appropriate screws or similar fasteners 38. As brought out in Figure 5, the purpose of this is to 40 adjust the lower edge of the plate 27a toward and from the table plate 20. Further, it will be noticed that the partition strip or body 27a has its lower corner portion undercut and beveled as indicated at 39, this cooperating with the adjustable edge of the plate 27a to provide a concentration 45 pocket. I might also point out in connection with Figure 5 that the approximate degree or inclination of the plate 27a in relation to the table plate 20 is 78 degrees as indicated by the arrow-head line 40.

50 55 Attention now comes to a refinement or modification depicted in Figure 7. In the other forms of the invention shown the plate 27a can be plain. In the arrangement seen in Figure 7, the plate is preferably corrugated, that is, provided with ribs defining between themselves grooves and thus preventing an undulated surface from end to end. The ribs 41 are of equal distances apart, that is from the left toward the right as seen in Figure 7. The two endmost ribs are more 60 widely spaced as indicated at 42. The arrows 43, 44 and 45 designate generally the course of action of the pulp.

65 70 Referring again to Figure 7 it will be observed that the end of the partitioning device 27 in practice terminates about one foot from the adjacent wall of the table. The adjacent pointed end of the crescent-shaped regulator 29 is disposed in approximate alignment with the pocket or groove defined by the undercut surface 39. This is

brought out by the dotted line. In practice the adjacent point is approximately one-quarter of an inch from the end of the divider or partition 27. The distance of the point from the partition is increased about one-quarter of an inch in each succeeding step. The device 29 is to be about eight inches in length and the left hand pointed end (Figure 7) laps the concentrate holes 21. This being, in practice, about three and one-half inches in diameter. The crescent-shaped separator itself is about two inches in height, this being two-thirds of the height of the partition unit 27.

Reviewing the principle of operation of the arrangement depicted in Figure 7 it is evident that the pulp and water coming in at the inlet 18 will travel along the rifled surface 41 of the plate 27b with reasonable velocity, the water and pulp contacting the riffles being agitated and thrown away from the rifled surface in a downward and outward direction as indicated by the various arrows 43. This spreads the pulp over the plate 20. When it reaches the end of the rifled partition the pulp will be washed away with more direct and added force over the regulator, that is, the first pointed end of the regulator 29. The heavier ores are washed down to and over the plate in such a manner that the heavier ores will remain below the lighter pulp on the plate and will (from natural gravity) gradually settle into the pocket or space 39. Then upon being forced and washed apart the regulator 29 will permit the heavier ores to settle directly into the exit 21 and will force the lighter ores and waste to wash around the outside, that is, the convex surface of the regulator 29 into the next sluice-way to be treated similarly.

It is thought that persons skilled in the art to which the invention relates will be able to obtain a clear understanding of the invention after considering the description in connection with the drawings. Therefore, a more lengthy description is regarded as unnecessary.

Minor changes in the shape, size and arrangement of details coming within the field of invention claimed may be resorted to in actual practice, if desired.

Having described the invention, what is claimed as new is:

1. In a concentrator and separator table unit for ore-pulp, a base plate, a transversely arranged divider partition on said plate extending from one side wall and terminating in spaced relation from the other side wall, a second divider partition extending from the last-named side wall and having its free end portion terminating in spaced relation to the first-named side wall, a discharge hole in the plate between the free outer end of the first-named partitioning divider and adjacent intermediate portion of the second divider, and a pivotally mounted manually adjusted regulator and deflector element on the plate having one end cooperable with the adjacent free end of the first-

named divider and its opposite end overlapping and cooperable with the discharge opening.

2. In an ore-pulp concentrating and separating table unit, a bottom and a surrounding marginal wall, a pair of transverse partition dividers on the bottom, a discharge opening in the bottom at the free end of one of said partitioning dividers and adjacent the intermediate portion of the second-named partitioning divider, and a crescent-shaped regulator element eccentrically pivoted on the base with one point adjustably movable toward and from the free end of the first-named partitioning divider and the opposite point overlapping and co-acting with the discharge opening, said regulator element being adapted to function not only as a valving element for the opening but as a deflector, whereby to cause certain of the currents to pass between it and the free end of the partitioning divider and other portions of the currents to pass and sweep around its curvate edge in the direction of the intermediate portion of the second-named divider.

3. In a structure of the class described, an ore pulp concentrator and separator table comprising a flat bottom, an intake in one end, a diagonal partition secured to said bottom and engaged at one end with the wall of a table adjacent said intake, the opposite end being spaced from the opposed wall of said table, said bottom having a discharge hole therein adjacent the last-named end of said partition said partitioning device being provided on one face with an undulated plate for riffling the mass of ore pulp, and a substantially crescent-shaped adjustably mounted regulator on the bottom of the table and having one pointed end adjacent the coordinated end of said partition, the opposite end shiftably covering a portion of said hole, this to govern the size of the latter.

4. In a structure of the class described, an ore pulp concentrator and separator table comprising a flat bottom, a diagonal partition secured to said bottom, said table having a surrounding upstanding wall, said partition being secured at one end of said wall, the opposite end thereof being spaced from an opposed parallel wall, said bottom having a discharge hole therein adjacent to the last-named end of said partition, said partition being substantially triangular in cross-sectional form to provide a bevel surface on one side, a plate secured to the opposite side, said plate being shiftably mounted to vary the distance of its lower edge toward and from the bottom, and that portion of the partition below the lower edge of said plate being undercut to coact with said bottom and plate, and a substantially crescent-shaped, adjustably mounted combined regulator and deflector on the bottom, the latter having one pointed end adjacent to and co-acting with the corresponding end of said partition, and the opposite end shiftably covering a portion of said hole, this to govern the size of the latter.

ERWIN R. McPHEETERS.
